[57] CLAIM

The ornamental design for a cosmetic compact, as shown and described.

DESCRIPTION

FIG. 1 is a top plan view of a cosmetic compact showing my new design;

FIG. 2 is a rear elevational view thereof, shown in an inverted position;

FIG. 3 is a front elevational view thereof;

FIG. 4 is a left side elevational view thereof, the side opposite being a mirror image of the side shown;

FIG. 5 is a bottom plan view thereof; and

FIG. 6 is a top perspective view of a cosmetic compact of my new design, shown in an open condition.

FIG. 1

FIG. 2
